RAIL GRINDING MACHINE

Arion S. Kalenborn, Redwood City, Calif., assignor to Welding Service, Inc., San Francisco, Calif., a corporation of California

Application January 13, 1930, Serial No. 420,351

2 Claims. (Cl. 51—178)

This invention relates generally to machines or apparatus for performing certain specific grinding operations upon the rails of railway tracks.

In the maintenance of railway tracks, it has been found highly desirable to provide transverse slots at the rail joints, these slots extending downwardly from the upper faces of the rail balls. A rail joint of this character is disclosed and claimed in patent to McClary, No. 1,752,566, dated April 1, 1930. While the advantages of such a rail joint construction are fully set forth in said McClary patent, it may briefly be explained that such a slot provided in a rail joint provides a space into which metal will flow thus preventing chipping thru relative movement between the adjacent rail ends.

It is an object of the present invention to devise a practical machine which will make possible rapid slotting of the rails at the rail joints with a minimum amount of time and labor.

It is a further object of the invention to devise a machine of the above character which will be simple in construction, relatively cheap to manufacture, and which can be manipulated by a single operator.

It is another object of the invention to devise a machine of the above character which can operate upon both rails of a railway track without the necessity of reversing the position of the frame of the machine.

Further objects of the invention will appear from the following description in which I have set forth the preferred embodiment of my invention. It is to be understood that the appended claims are to be accorded a range of equivalents consistent with the state of the prior art.

Referring to the drawings:

Figure 1 is a plan view illustrating a machine incorporating the present invention.

Fig. 2 is a side elevational view of the machine shown in Figure 1.

Fig. 3 is an enlarged detail, partly in cross section, illustrating the manner in which my machine makes possible cutting a transverse slot in a rail at a rail joint.

Fig. 4 is a side elevational view of a rail joint illustrating the manner in which the slot is formed.

Fig. 5 is a plan view of a rail joint after the slot has been formed.

My invention can be outlined briefly as comprising a suitable cutting tool, such as a grind wheel, which is carried by a suitable frame and constrained to move in such a manner as to cut a

transverse slot in a rail. Thus referring to Figs. 1 and 2, I have shown a suitable frame 10 adapted to be disposed upon the rails 11 and 12, of a railway track. In this instance the frame is formed by longitudinal members 14 connected together by 5 end members 16. Frame 10 may be provided with wheels for operating upon the tracks 11 and 12 but for simplicity it has been shown as resting directly upon the rails, so that in moving the machine from one joint to another, it is simply slid 10 upon the rails. Depending lugs 17 can be provided for retaining the frame in proper operating position.

Disposed upon the frame 10 in such a manner that it can be shifted transversely of the track, I 15 provide a suitable carriage 19. This carriage can be conveniently formed of upright spaced side members 21, having their upper portions interconnected by members 22. The lower portions of side members 21 are connected to members 23, 20 which can be conveniently formed as angles, which serve to track the carriage upon the longitudinal frame members 14.

The cutting tool or grind wheel 26 is normally restrained to move in a substantially vertical 25 plane, or in other words in a plane substantially at right angles to the rails. While various means may be utilized for effecting vertical adjustment of grind wheel 26, in this instance I utilize a swinging or pivoted arm structure 21, to which 30 grind wheel 26 is journaled. It is also preferable to have arm 21 support an electric driving motor 28. The particular arm structure which I have utilized in this instance consists of a frame 29 within which the housing of motor 28 is mounted. 35 Shafts 31 project from the end of frame 29, and are journaled by suitable bearing members 32, which in turn are mounted upon the side members 21 of the carriage 19. Grind wheel 26 is secured to the end of a rotatable shaft 33, and this 40 shaft is journaled in a suitable bearing member 34. Bearing member 34 is rigidly connected to the housing of motor 28, by means of spaced members 36. For driving the grind wheel 26, the shaft of motor 28 and shaft 33 are provided 45 with pulley wheels 37 and 38 respectively operably engaged by a driving belt 39.

For providing precise adjustments of the arm structure 21, I preferably provide a worm gear 41 upon the end of said shaft 31, and this gear 50 is operably engaged by a worm 42. Worm 42 can be rotated by means of hand wheel 43, so that by manual rotation of this wheel, arm structure 21 and thus grind wheel 26 can be raised or lowered any desired amount.

The operation of the invention can be understood by reference to Figs. 3 and 4. As shown in Figs. 4 and 5, it is desired to cut a slot 44 extending downwardly from the upper faces of the rail balls 46, at the joint between the two adjacent rail sections. The width of the cutting face of grind wheel 21 is preferably such that it is slightly less than the width of the desired slot 44. The operator then moves carriage 19 to a position adjacent the rail joint to be slotted, and the grind wheel is adjusted to proper position by hand wheel 43, to start a slot across the joint as shown in Fig. 3. Carriage 19 is moved manually to gradually advance the grind wheel across the rails. Generally a single cut is sufficient to produce a slot of proper depth, although one or more additional cuts may be made if desired. If a joint upon the other side of the track is to be slotted, frame 10 need not be reversed, but the operator simply moves carriage 19 to the other side of the track, and then properly positions grind wheel 26 for making a similar cut. It is to be noted that grind wheel 26 is normally located upon one side of the center line of carriage 19. Therefore for one operating position of the carriage, the carriage center line is within the rails, while for operating upon the other side of the track without reversing the position of the frame, the center line of the carriage must fall outside the track. This is made possible with my apparatus, by making longitudinal frame 14 substantially longer than the gauge of the track as shown in Fig. 1, so that when carriage 19 is positioned with its center line outside of the track, it is practically supported. The extension of longitudinal members 14 beyond both sides of

the track, makes possible universal application of my machine. In other words irrespective of the position of frame 10, both rails of the track can be operated upon.

Generally it is preferable to employ an electric motor for driving the grind wheel, since a source of electrical power is generally available or can be furnished by a portable generating outfit. However if desired other motive means, such as an internal combustion engine, can be employed.

I claim:

1. In a rail grinding apparatus, a frame adapted to rest upon the rails of a railway track, a carriage slidably supported by said frame and adapted to be moved transversely of said track across the frame, an arm pivotally secured to the carriage and adapted to swing in a substantially vertical plane, a grind wheel journaled to said arm and adapted to rotate about an axis normal to said plane, whereby said wheel can cut a transverse slot at a rail joint, a motor fixed to said arm, means operably connecting said motor to said grind wheel, and means for adjusting the position of said arm.

2. In a rail grinding apparatus, a frame adapted to span the rails of a railway track, said frame having a length substantially greater than the gauge of the track, a grind wheel, means including a carriage movably mounted on said frame and serving to operably support the grind wheel with the plane of the wheel substantially at right angles to the rails, said frame being of sufficient length to permit shifting of the carriage to grind a transverse slot in either rail without reversing the position of the frame.

ARION S. KALENBORN.
